UNITED STATES PATENT OFFICE.

WILLIAM H. WILDER, OF GARDNER, MASSACHUSETTS.

OIL-BURNER.

SPECIFICATION forming part of Letters Patent No. 653,893, dated July 17, 1900.

Application filed April 19, 1897. Serial No. 632,858. (No model.)

To all whom it may concern:

Be it known that I, WILLIAM H. WILDER, a citizen of the United States, residing at Gardner, in the county of Worcester and State of Massachusetts, have invented certain new and useful Improvements in Oil-Burners, of which the following is a specification, reference being had therein to the accompanying drawings.

10 My invention is designed to provide an oil-stove adapted to be used with petroleum or ordinary coal-oil and to generate vapor from the surface of the oil in a suitable holder and is distinguished from vapor-burner stoves in that a holder is provided adapted to receive a limited supply of oil, and this oil is vaporized from its surface, the supply being maintained, increased, or diminished at the will of the operator, while in the vapor-burner 15 stoves using petroleum a vapor-holder is provided, the oil being vaporized as fast as it enters the holder, filling the same by gravitation and rising through a convenient space to a combustion-chamber.

20 My invention includes a very simple form of oil-holder, with a combustion-chamber above the same vertically movable for lighting purposes and easily removable for any purpose, this chamber comprising perforated 25 tubes, with means for shielding the same from air-currents while feeding thereto the proper amount of air necessary for perfect combustion.

The invention also includes many details 30 of construction of importance in a stove of this class.

In the accompanying drawings, Figure 1 is a sectional elevation, and Fig. 2 a front elevation, of a stove embodying my improvements. Fig. 3 is a plan view of the burner. Fig. 4 is a detail sectional view of the oil-holder and supply-pipe. Fig. 5 is a detail of the initial-lighting means.

I have shown a convenient form of frame 45 at A, comprising a sheet-metal top and suitable legs and braces, which may be of any ordinary or improved construction.

The burner comprises an oil-holder and a combustion-chamber composed of perforated 50 tubes and certain accessories, as will be hereinafter more fully described. The oil-holder is preferably made of drawn sheet metal,

forming an annular channel, as shown in the sectional view, of considerable depth, the lower part being contracted and the upper part being enlarged by reason of the upper 55 walls flaring outwardly. The holder is shown at B and is surrounded by a drum C, which conceals the same and supports it by a bead turned over the upper edge of the holder, 60 while the drum itself rests upon a cross-bar a, supported upon the frame by the hooks 1 and nuts 2. The drum is open at the bottom and serves to not only conceal the oil-holder, but also other operating parts, to be more 65 fully described hereinafter. The drum is held securely to the cross-bar a by hooks and nuts similar to those which hold the cross-bar to the frame. The shape of the oil-holder gives a depth sufficient to maintain a supply of oil 70 in the lower part thereof, and the enlarged space in the upper end of the holder gives a greater vaporizing-surface and also provides for the use of an initial-lighting device b, which may be of asbestos or any suitable material adapted for the purpose. It will be 75 understood that this initial-lighting medium does not operate in the manner of an ordinary wick to lift the oil from a supply by capillary attraction, but is composed of some 80 mineral or metallic substance adapted to lift initially sufficient oil to start the flame, and as soon as this lifting medium heats up it repels the oil and ceases to work as a wick or lifting medium for the oil. The oil fills 85 the burner and almost submerges the lighting medium, and after the initial lighting vaporization takes place direct from the surface of the oil, and the action is not affected in any way by the lighting medium. It is of 90 importance when this initial-lighting medium is used to locate it properly, so that it will be in such relation to the top of the oil-holder as to always be capable of lighting easily, but not too high, so as to be so far above the 95 oil as to coke and get hard. As soon as the stove has been started through the initial-heating means the oil in the holder begins to vaporize on the surface, and the oil is continually supplied to the holder from the reservoir and in such quantities as may be required by the work being done on the stove, the supply being under the control of the operator, who may make it regular or flood the 100

burner or drain it, according to the requirements of the work.

- The combustion-chamber comprises two concentric tubes perforated and suitably secured together, with shields upon the interior of the inner tube and the exterior of the outer tube adapted to protect the combustion-space from the injurious effects of the air-currents and at the same time properly feed just the right quantity of air in order to make the combustion perfect. The tubes are held together by rods *c*, crossing each other at right angles, and the shield for the inner tube is made of corrugated metal, with the upper ends of the corrugation bent inwardly to close the channels at the upper end formed by the corrugations. The shield (indicated at *D*) extends below the end of the inner tube and has its lower end closed by a cap *d*, held in place by a hook which passes over a rod *e*, extending through between the walls of the shield, the lower end of the hook engaging a nut, as shown at *f*. The outer shield *E* is made of corrugated metal and encircles the outer combustion-tube, as shown, and the channels of the shield formed by the corrugations are preferably open at the top and bottom. The projecting end of the shield *D* (indicated at *F*) is adapted to pass down through the central opening of the oil-holder, while the lower end of the outer combustion-tube is made slightly flaring and adapted to rest upon the shoulder *g* of the oil-holder, thus forming a close joint.
- In order to start the stove, it is necessary to lift the combustion-chamber, so as to expose the initial-lighting wick to the match, and this is readily done by a disk *h*, held within the central space inclosed by the oil-holder, this disk being guided by a cross-bar *a* and bracket *a'*, and it is given vertical movement by a lifting-lever *i*, which engages a loop *k*, the lever being bent in its length, so as to raise the disk *h* and the combustion-chamber supported thereby on a half-turn of the handle of the lifting-lever *i*, and the parts stay in their elevated position until the lever is turned back.
- It will be seen that the arrangement of the shield is such that the air coming in at the bottom of the drum *C* finds outlet to the combustion-space through a series of vertical channels closed at the top, but in connection with the combustion-space through the perforated tube, and as these channels are practically independent of each other the air is fed in columns through the perforated inner walls of the combustion-space, and thus the combustion is not affected by irregular quantities of air or by drafts. The outer shield protects the outer combustion-tube from drafts and currents of air, but by reason of its series of corrugations provides a number of channels around the outer periphery of the outer combustion-tube, so as to feed air thereto in vertical columns.

The oil may be fed from a reservoir *G* of or-

dinary or improved construction directly to the oil-holder, the feed being regulated by the demand, as in the ordinary student-lamp, and further controlled by a needle-valve, as indicated at *l*; but I prefer to feed the oil through a chamber *H*, connected with the main supply-pipe *m* by a branch pipe *n*, leading from the valve *l*. This branch pipe *n* is connected to the chamber *H* through a nipple *n'*, provided with an opening on one or both sides, which may be left open or covered by glass or mica to form a sight-feed, and thus the flow of the oil can be observed as it drops from the end of the branch *n* into the chamber *H*. Contained within the chamber and vertically movable therein is a plunger and rod operating to displace the oil in the chamber *H* and force it into the oil-holder *B* of the burner or drain the oil from the holder, according to the position of the plunger. I term this a "displacer," and I have shown it at *I*. The chamber *H* is connected to the holder by a pipe *p*, entering the holder at the bottom thereof and tapping the chamber *H* at a position above the bottom, as the bottom of the chamber *H* is upon a lower level than that of the oil-holder *B*. It will be seen that when the displacer is raised the oil will drain out of the holder *B* into the chamber *H*, and when it is desired to restore the oil to the holder the displacer is moved down, and when in its lowest position the feed of the oil will be over and around it through the pipe *p* into the holder.

If desired, I may make the displacer to be manually operated independent of the valve mechanism, and instead of feeding the oil through the drain-chamber to the oil-holder the oil may be fed direct to the holder; but I prefer, as shown in the drawings and particularly in Fig. 1, to connect the rod of the displacer with the valve mechanism, so as to make the action automatic, and thus provide for the lifting of the displacer on the closing of the valve and the lowering of the displacer on the opening of the valve. The handle of the valve has cast with it a cam-flange *q*, which engages the notched end of a lever *r*, pivoted on the valve-bracket *s* and having its opposite notched end *t* connected to the end of the rod of the displacer.

The initial-lighting medium *b* I prefer to make of asbestos or some other material which is practically indestructible, and it will be understood that in the present instance this does not have any means for lifting it, as in the case of an ordinary wick, it being permanently placed in position, with its upper portion projecting slightly above the fuel-holder, so as to be accessible when the combustion-chamber is lifted, and at the same time the end should not project high enough to become charred, as I aim to have it in such relation to the normal level of the oil as to keep it moist. It will also be observed that I make the lighting medium with a notched lower edge so that it does not extend to the bottom

of the fuel-holder except at the points, and under certain conditions it may be desirable to shorten the lighting medium and make it of less depth than the fuel-holder all around.

5. It will be observed that I supply the oil to the bottom of the oil-holder, and this produces the best results. In order to make an oil-tight joint, I enlarge the wall of the oil-holder, as shown in full lines, Fig. 4, at the 10 point where the connection is made, bring the end of the oil-supply pipe p directly beneath the bottom of the oil-holder, and then pass a screw p' down through an opening in the bottom of the holder to engage the end of the pipe p , forming an oil-passage through the screw, as at 3, and thus a secure and oil-tight connection is made.

While I have shown and described an oil-holder having a lower contracted part and an upper part enlarged or flaring, with an igniting medium seated in the contracted portion and extending between the walls of the enlarged part, I do not claim this combination of the holder and the igniting medium in this application, this being made the subject of a divisional application, Serial No. 701,160. The present case is directed to a holder capable of being drained or emptied or to maintain a column of oil as a base of vaporization, 30 said holder being used with a combustion-chamber or with means for controlling the supply of liquid to the holder.

I claim—

1. In an oil-burner, a combustion-chamber, 35 an oil-holder constructed to be drained or emptied and adapted to maintain a column of oil as a liquid-base for vaporization and an oil-supply.

2. In an oil-burner, a combustion-chamber, 40 an oil-holder constructed to be drained or emptied, said holder having a depth greater than its width to maintain a column of oil as a liquid-base for vaporization, and an oil-supply substantially as described.

45 3. In an oil-burner, an oil-holder having a depth greater than its width, an oil-supply and means for causing the oil to fill the burner for ignition, to lower it for normal burning, to maintain a body of oil therein 50 while the stove is burning, and for draining to extinguish, substantially as described.

4. In an oil-burner, an oil-holder, an initial-lighting medium therein and an oil-supply with means for causing the oil to flood 55 the holder to submerge wholly or partially the lighting medium for igniting purposes and to lower the oil for normal burning while maintaining the feed of oil.

5. In an oil-burner, an oil-holder and an oil-supply with means for causing the oil to flood the holder for igniting purposes while maintaining the feed of oil.

6. In a burner, a combustion-space having 60 perforated walls and a channeled outer shield therefor, adapted to admit the air to the space in vertical columns.

7. In a burner, a combustion-space having

perforated walls and an inner channeled shield adapted to admit air to the space in vertical columns, substantially as described. 70

8. In a burner, a combustion-space having perforated walls, an inner shield forming an air-space and having a series of channels, said channels being closed at the upper end, substantially as described. 75

9. In a burner, a combustion-space having perforated walls and an inner shield therefore, said shield being closed at its upper end and at its center, substantially as described.

10. In a burner, a combustion-space having 80 perforated walls and a channeled or corrugated inner shield closed at its upper end and having a closed center, substantially as described.

11. In combination, inner and outer perforated combustion-tubes, a corrugated or channeled outer shield and a corrugated inner shield, said shields adapted to supply air to the combustion-space in a series of vertical columns, the inner shield being closed at its 90 upper end and having a closed center, substantially as described. 85

12. In combination with a fuel-holder, combustion-tubes having perforated walls supported thereby and an inner shield for the 95 combustion-space extending below the bottom of the combustion-tubes and channeled to receive and direct the air to the inner tube, said shield being closed at its upper end, substantially as described. 100

13. In combination with perforated combustion-tubes, a corrugated outer shield encircling the outer tube, a corrugated shield within the inner tube having the corrugations closed at the upper end and open at the 105 lower end below the level of the combustion-tubes, said inner shield having a closed bottom, substantially as described.

14. In combination with a liquid-fuel holder having an annular space for the fuel and an inner and outer shoulder on each side of the channel with an open central portion, a combustion-chamber comprising perforated tubes, the said tubes being adapted at their lower ends to rest upon the shoulders of the 115 holder and a corrugated shield for the inner combustion-tube, the lower end of said shield passing through the open center of the holder, substantially as described. 120

15. In a burner, a liquid-fuel holder, a drain-chamber, a displacer within the drain-chamber, an oil-supply leading to the drain-chamber, a valve controlling the supply and a connection between the valve and displacer for operating the two simultaneously, substantially as described. 125

16. In combination with a burner, a reservoir, a valve for controlling the supply of oil therefrom and a holder or auxiliary reservoir between the valve and the burner with means 130 for supplying the burner from said holder while maintaining the feed, substantially as described.

17. In combination with a burner, an oil-

4
supply, and an oil-chamber interposed between the burner and main supply, and means for supplying the burner quickly from the interposed chamber without interfering with the regular feed and for draining the burner into said interposed chamber, substantially as described.

18. In a burner, an oil-holder in combination with an oil-supply, a valve controlling this supply and an auxiliary oil-chamber interposed between the valve and burner, with

means for automatically flooding or draining the burner by the operation of the valve and at the same time allowing or cutting off the regular feed from the main reservoir, substantially as described. 15

In testimony whereof I affix my signature in presence of two witnesses.

WILLIAM H. WILDER.
